(57) **CLAIM**

I claim the ornamental design for a bicycle saddle, as shown and described.

DESCRIPTION

FIG. 1 is a top perspective view of a bicycle saddle showing a first embodiment of my new design;

FIG. 2 is a front elevation view of FIG. 1;

FIG. 3 is a top plan view of FIG. 1;

FIG. 4 is a bottom plan view of FIG. 1;

FIG. 5 is a right side elevation view of FIG. 1, the left side view being a mirror image thereof;

FIG. 6 is a rear elevation view of FIG. 1;

FIG. 7 is a top perspective view of a second embodiment thereof; and,

FIG. 8 is a front elevation view of FIG. 7.

The broken lines in the drawings illustrate portions of the bicycle saddle which form no part of the claimed design.
